UNITED STATES PATENT OFFICE.

BERNARD F. STENZ, OF NEW YORK, N. Y., ASSIGNOR TO SIMPLEX LITHOGRAPH COMPANY, OF NEW YORK, N. Y., A CORPORATION OF NEW YORK.

SAMPLE-CARD.

1,047,849.

Specification of Letters Patent. Patented Dec. 17, 1912.

Application filed October 5, 1912. Serial No. 724,105.

To all whom it may concern:

Be it known that I, BERNARD F. STENZ, a citizen of the United States, and a resident of the city of New York, borough of Manhattan, in the county and State of New York, have invented a new and Improved Sample-Card, of which the following is a full, clear, and exact description.

The present invention relates to sample cards for displaying samples of textile fabrics.

It is now customary in displaying textile fabrics to cut up material into pieces and attach them to a card, or "mount", and this practice entails a large expense, not only for the material which is cut up into samples, but also for the labor incident to the cutting of the material and the attaching of the samples to the cards, and it is with the object of producing a sample card which shall accurately display samples of textile fabrics without the necessity of employing samples actually cut from the goods that the present invention was produced.

My invention consists of the sample card which will now be described and claimed.

A sample card embodying my invention is shown in the accompanying drawing, in which—

Figure 1 shows a front view of one form of such card; and Fig. 2 shows a vertical section taken on line 2—2 in Fig. 1.

Similar reference characters will be used throughout the specification and drawing to designate corresponding parts.

My improved sample card comprises a body portion 1, which obviously may be of any suitable shape and dimension, and is constructed of any suitable material, but preferably of cardboard of sufficient thickness and stiffness to maintain its shape in handling, and yet sufficiently thin to receive the embossed impressions as will be hereinafter described. Upon one face, the body portion 1 carries a raised panel 2 formed in the body portion 1 by an embossing process, and said panel upon its face represents accurately the pattern and weave of the textile fabric which it is intended to represent as shown at 8. The panel 2 may be of any shape in outline, but will ordinarily be rectangular in shape and preferably oblong as shown, and it will have sharply defined marginal edges 4 such as

would be formed were a piece of fabric actually cut to the size shown and secured to the body portion 1, the edges 4 being raised above the body portion 1, a distance substantially equal to the thickness of a piece of textile fabric. The panels 2 are formed by suitable dies using a sample of the fabric as a pattern, and such dies duplicate accurately the pattern and weave of the fabric which it is intended to display, and are used to emboss the body portion 1, to form the panels 2 in the ordinary manner of embossing. The panel 2 is in effect a replica of the piece of goods which formed the pattern for the die. Any desired number of panels 2 may be formed in the body portion 1 corresponding in number to the number of samples which it is desired to display, and they may be arranged on the body portion 1 in any desired manner. In the drawing, I have shown four such panels illustrating and displaying four different samples of textile material.

As it may be desired to enable the observer to determine the structural characteristics of the fabric displayed by the panels, the sample card will preferably be provided with a sample of the actual material itself, as shown at 6, which sample may be of any suitable size or shape in outline and will be secured to the body portion 1 of the sample card along one of its edges by a suitable adhesive as shown at 8, leaving the main portion detached so that it may be lifted and subjected to the desired examination to determine its quality. All other samples, however, will be accurately displayed by the panels 2 which, as before stated, consist of an embossed surface which reproduces in all particulars the characteristic weave and pattern of the fabric which it is intended to represent.

It is, of course, to be understood that samples of colored material may be displayed by embossed panels by printing the colors which appear in the fabric to be displayed. This modification of the invention, is of great importance, in that it permits the color and pattern of the fabric sample to be exactly reproduced, as well as the characteristic weave and body of the fabric.

By my improved sample card, I almost entirely do away with the practice of cutting up textile materials and attaching them

to cards which has for so long been the common practice for producing sample cards of this nature and at a great saving both of time and materials.

5 Having thus described my invention, I claim as new and desire to secure by Letters Patent:

1. A sample card for displaying samples in the similitude of textile fabrics, comprising a body portion and an embossed panel struck up from said body portion having a surface forming a replica of a sample of textile material.

10 2. A sample card for displaying samples in the similitude of textile fabrics, comprising a body portion, and an embossed panel struck up from said body portion having a surface forming a replica of a sample of textile material and sharply defined edges 20 raised above the body portion a distance substantially equaling the thickness of a sample of textile material.

25 3. A sample card for displaying samples in the similitude of textile fabrics comprising a body portion, and an embossed panel struck up from said body portion forming a replica of a sample of textile material, and

a sample of textile material attached to said sample card.

4. A sample card for displaying samples 30 in the similitude of textile fabrics, comprising a body portion, and a plurality of embossed panels struck up therefrom representing replicas of samples of textile material differing in pattern from each other, 35 and arranged symmetrically with relation to each other.

5. A sample card for displaying a sample in the similitude of textile fabric having struck up thereon a replica of a sample of 40 the textile material to be displayed.

6. A sample card for displaying a sample in the similitude of a textile fabric, said card having a surface corresponding to the characteristic weave of the pattern of the fabric, 45 and being colored in correspondence with the color and design of the fabric.

In testimony whereof I have signed my name to this specification in the presence of two subscribing witnesses.

BERNARD F. STENZ.
